UNITED STATES PATENT OFFICE.

WALTER W. KANTACK, OF ST. ALBANS, LONG ISLAND, NEW YORK, ASSIGNOR TO
ALFRED VESTER SONS, INC., OF PROVIDENCE, RHODE ISLAND, A CORPORATION
OF RHODE ISLAND.

DESIGN FOR A PLATE FOR LIGHTING FIXTURES.

Application filed November 3, 1926. Serial No. 19,586. Term of patent 7 years.

To all whom it may concern:

Be it known that I, WALTER W. KANTACK, a citizen of the United States, residing at St. Albans, Long Island, in the county of Queens and State of New York, have invented a new, original, and ornamental design for a Plate for Lighting Fixtures, of which the following is a specification, reference being had to the accompanying drawing, forming part thereof, in which—

Fig. 1 is a front view showing my new design;

Fig. 2 is a partial plan view, only part of the ornamentation being shown, it being understood that the remainder is identical.

I claim—

The ornamental design for a plate for lighting fixtures, as shown.

WALTER W. KANTACK.
